Attorneys

UNITED STATES PATENT OFFICE.

FRANK SEMPLE WILCOX, OF UNION, SOUTH CAROLINA.

PROCESS FOR SPLICING, PLAITING, AND SEAMING YARNS AND THREADS.

Application filed September 27, 1923. Serial No. 665,146.

To all whom it may concern:

Be it known that I, FRANK S. WILCOX, a citizen of the United States, residing at Union, in the county of Union and State of South Carolina, have invented certain new and useful Improvements in Processes for Splicing, Plaiting, and Seaming Yarns and Threads; and I do hereby declare the following to be a full, clear, and exact description of the invention, such as will enable others skilled in the art to which it appertains to make and use the same.

The present invention relates to an improved process for splicing, plaiting and seaming yarn, thread and the like.

An object of the present invention is to provide a process wherein separate strands of yarn or thread may be readily distinguishable during the various knitting and sewing operations and facilitates the operator in determining the condition of the work as it proceeds, and to also render more distinguishable any defects which may occur in the finished article after it has been completed and removed from a knitting or other machine.

Another object of the invention is to provide a process which embodies the treatment of the thread or yarn with a transitory dye or color so that as a number of strands of the thread or yarn are introduced into a machine, or the like, and brought into certain definite relations, such relations may be determined as the work proceeds and the article is formed.

It is well known to those skilled in the art that splicing and reinforcing of hosiery is done by introducing an extra thread of yarn in the parts to be reinforced, such as in hose: the heel, the toe and sole and also the ankle in half hose while in ladies' hose, the splicing is additionally effected at the top of the leg known as the "garter top".

The splicing yarns or fibers used are obtained by the manufacturer in their natural color which is generally white and which are not readily distinguishable from the white color of cotton, wool, silk and silk fiber used in the body of hosiery. It is thus evident that when there is a total failure of a machine to function in the splicing operation, the operative can notice this condition by failure of the yarn to run from the bobbins but this failure cannot be easily noticed as there may be a number, half a dozen or so, bobbins with various yarn on them which

would normally be out of action at such times so that the ability to distinguish at a glance whether the splicing is being carried on is highly useful, important and necessary.

During the splicing operation the mechanism frequently does not cease but various defects may take place and not be readily noticed, among which may be mentioned the following:

The splicing may not be introduced at the proper time, or operate through the proper distance.

The splicing may be skipping.

There are many other irregularities, such as the failure to follow around the stocking for the right distance, and the like.

It is extremely difficult and only by very close examination that the above defects may be discovered on account of the fineness of splicing yarns and similarity of color between the same and the body of the hose.

It is a further object of this invention to provide a process wherein these defects may be readily and quickly observed so that correction thereof may be made. Further, after the hosiery is knitted the defective goods may be more easily and quickly distinguished from the perfect ones and may thus be separated, the present invention thus greatly facilitating and making more accurate this inspection and separation of the completed articles.

A still further important feature of this invention is in the process of plaiting yarn as in the plaiting of yarns the fabric is so knitted that one kind of yarn will be visible on the exterior or outer surface of the fabric while another quality or kind of yarn is used on the interior. This is common with the following knitted combinations:

Silk with cotton backing, fiber silk and cotton, wool and cotton, and many other combinations.

The efficiency in the plaiting operation depends on the complete covering of the inferior yarn or strand with the yarn or strand of the better grade. When the yarns are of the same natural color it requires a very close inspection to determine whether the plaiting device is properly set. The present invention therefore aims to provide a process wherein defective setting of the plaiting device may become immediately apparent. It is the usual custom to carefully inspect the plaiting devices once or

twice a day and to take a chance that these devices will stay as adjusted.

By the present invention there may be easily kept an accurate check at all times of the operation of the plaiting device.

A further object of the invention is to provide a process which may be practiced not only in splicing or plaiting yarn but also in sewing or seaming fabrics and in all such operations where it is an advantage to distinguish the yarns, threads or strands from one another and from the body of the fabric.

In order to bring out the novel features of the present invention the following is a detailed description of the present preferred manner of practicing the present invention wherein reference is made to the accompanying drawing which shows:—

A side elevation of a knitted article in the form of a half hose showing splicing thereon which is made according to the process of this invention.

Referring to the drawing which shows a half hose having a body part 10 of one color which is usually white, the knitting operation is carried on in any well known manner as is also the splicing operation to apply the splicing 11 which may be placed on the article at the desired points, such as at the toe, heel, and ankle as shown in the drawing and also along the sole or bottom portion of the hose. This splicing is usually of the same natural color as the body 10 and hence is not readily distinguishable from the fibers or yarn of the body 10 and defects in the splicing operation cannot be readily determined.

According to the present invention the splicing yarn is first treated with the color or dye different from the color of the body 10 so that the portions 10 and 11 will be readily distinguishable one from the other and the operation of splicing may be observed and inspected as it proceeds to easily and readily catch up defects and thus remedy them or prevent further defects of a like nature. The result is that the article produced is as shown in the drawing with the body 10 of one color and the splicing 11 of a different or contrasting color.

The invention further provides in the process that the color be of a transitory nature so that while for the purposes of the splicing and knitting operation the yarn of the different parts of the article may be readily distinguishable, the color or dye is transitory so that it may be removed from the yarn or

thread by the ordinary laundering process so that the article as a whole may be subsequently dyed of a uniform color or as otherwise may be desired. The transitory color in the splicing is for the purposes of contrast between the yarn or thread during the operation only and after the article is formed it is no longer needed, save for inspection purposes, and is not an objection to the later dyeing and treating of the hose.

This coloring of the splicing yarn is advantageous not only during the operation of making the article to insure a better formed article, but is also advantageous in the inspection and separation of perfect from defective articles so as to readily separate out seconds and the like which have minor imperfections.

This treatment of the yarn or thread with a transitory dye or color may also be used to considerable advantage in plaiting and wherein it is even more important than in the knitting of hosiery to continuously inspect the plaiting device so as to quickly determine when the same moves out of adjusted position so as to effectively cover the inferior with the better yarn or thread.

Any suitable dye or coloring of a transitory nature may be used as a number of the same are readily obtainable on the market, and one which has been found practically successful is azo yellow A5W which is made by the National Aniline & Chemical Company of Charlotte, North Carolina, and known by them as Schultz Number 928.

It is of course understood that this process may be practiced not only with the use of yarns in plaiting and splicing as above particularly pointed out, but may also be practiced in the use of threads or other strands for sewing or other operations where it is deemed necessary to observe these operations as they proceed for determining the accuracy and nature of the work.

What is claimed is:—

That process of splicing, plaiting and seaming yarns and thread which comprises the treatment of the yarn and thread with a transitory coloring matter different from the color of the fabric to which the yarn and thread is to be applied and the carrying out of the application of the thread or yarn whereby said application may be observed throughout the entire operation and defects may be readily noticed.

FRANK SEMPLE WILCOX.
